EXPANSIBLE BINDER

Filed June 18, 1930

UNITED STATES PATENT OFFICE

HUGH G. BUCHAN, OF PHILADELPHIA, PENNSYLVANIA

EXPANSIBLE BINDER

Application filed June 18, 1930. Serial No. 461,930.

This invention relates to an expandable binder of that type having relatively adjustable halves whereby the capacity thereof may be increased or decreased as desired.

5 In the past such types of binders usually employed telescopic posts and slotted leaves were necessary for engaging the posts. This invention eliminates the telescopic posts and employs a construction whereby leaves with 10 closed holes may be used. Another feature of invention resides in an automatic locking mechanism for adjusting the two halves or 15 clamping members of the binder and is of such a character as to facilitate the closing of the binder.

The invention comprises the novel structure and combination of parts hereinafter described and more particularly pointed out and defined in the appended claims.

20 In the accompanying drawing which illustrates a preferred form of this invention and in which similar reference numerals refer to similar features in the different views:

25 Figure 1 is an interior fragmentary plan view of a binder involving this invention.

Figure 2 is a fragmentary sectional view taken upon the line II-II of Figure 1, looking in the direction of the arrows.

30 Figure 3 is a fragmentary sectional view taken upon the line III-III of Figure 2 looking in the direction of the arrows.

Figure 4 is a sectional view taken upon the line IV-IV of Figure 1 looking in the 35 direction of the arrows.

The invention has been illustrated in connection with a well known binder, parts of which are illustrated in the drawing and which consists of the two rigid angular or 40 clamping members 1 and 2, the bottoms of which slidingly overlap so that the two halves or angular members of the binder may be adjusted toward or from each other. The usual covers 3 are hinged respectively 45 to hinge plates 4 and 5 secured to the inner walls of the angular members.

In order to guide the two parts of the binder in their adjustment and to prevent the same from relative shifting movements 50 in a longitudinal direction, a tubular mem-

ber 6 is secured to the member 1 adjacent each end of such member and a pair of guide rods 7 are secured to the wall of the other member for telescopic relation with the tubular members 6.

55 The aforementioned covers 3 are suspended from hinge rods 8 confined in cylindrical bearing lugs upon the tops of the hinge plates 4 and 5. According to this invention, a post plate 9 is hinged upon one of the hinge rods 8 and supports a plurality of impaling posts 10 upon which loose sheets may be impaled when the plate 9 is swung upwardly to bring its plane into alignment with the plane of the adjacent cover. In 60 connection with this operation, it might be mentioned that the plate 9 is so hinged as to provide sufficient friction to normally retain the plate 9 in any position to which it may be adjusted.

70 Upon the other hinge plate which in the present instance is the one designated as 4, there is a removable post plate 11 having a plurality of posts 12 thereon, the points of which are adapted to enter apertures 13 in 75 the plate 9 when the binder posts are not in expanded relation. The post plate 11 is provided with apertures 14 for receiving the points of the posts 10 when the binder is not expanded. The plate 11 normally rests 80 upon the guide posts 6 and it is provided with struck-out lugs 15 that engage under the hinge upon the binder part 1 in order to properly position the same and prevent the same from upward movement. It might 85 be here mentioned that this second post plate 11 is necessary to hold a portion of the leaves when the binder is expanded as shown in Figure 1.

90 The mechanism for automatically locking the binder in its expanded or adjusted position will now be set forth. Upon the angle member 1 there is secured a ratchet bar 16 having teeth 17 which slope toward the member 1. This ratchet bar is provided with a slot 18 for a purpose that will later appear. An inverted U-shaped housing 19 is secured upon the bottom of the other angular member 2 by means of suitable rivets 95 20, one of which extends thru the slot 18 in 100

the ratchet bar; the housing 19 having a slot for receiving the ratchet bar as shown in Figures 2 and 3.

It will be noted that the housing 19 extends substantially the length of the binder. Its purpose is mainly to house a latch bar 21 having a thumb piece 22 projecting therebeyond whereby the same may be operated. This latch bar has a slot 23 thru which the ratchet bar 16 passes and the forward wall of this slot serves as a detent 24 for engaging the ratchet bar 16. The latch bar 21 is provided with an abutment 25 (Figure 3) and a compression spring 26 is positioned 10 between the abutment 25 and an adjacent rivet 20 and is effective for normally maintaining the latch bar 21 in engagement with the ratchet bar 16.

When it is desired to expand the binder, 20 the latch bar 21 is pushed inwardly to disengage the ratchet bar 16 when the binder parts may be moved apart. When it is desired to close or contract the binder, the two parts are merely pushed together; the detent 24 readily riding over the ratchet teeth during such movements; and the rivet 20 in the ratchet bar passing freely in slot 18 thereof.

When it is desired to impale additional 30 leaves or add new leaves, the binder will first be opened as previously explained by pushing in the latch bar and separating the parts. The plate 9 will then be swung up as the sheets are swung over upon the cover 35 adjacent the plate 9. The posts 10 will then occupy a vertical position. In doing this; the plate 11 will of course be readily disengaged from the member 1 and will be positioned upon the top of the sheets. The plate 40 11 may then be removed from the sheets and additional sheets impaled upon the posts 10. After these additional sheets have been impaled upon the posts 10, the plate 11 may then be placed upon the sheets, the posts 12 45 thereof entering suitable apertures provided therefor in the sheets. The sheets clamped between the two plates may then be swung down into proper position in the binder and the loose plate 11 adjusted to bring the lugs 50 15 under its hinge rod and the two parts of the binder may then be pushed together until the sheets are firmly clamped between the two parts.

From the foregoing it will be apparent 55 that a novel and handy form of binder has been disclosed in which the leaves do not require open slots or holes as heretofore, and in which the loose sheets can be more easily manipulated.

I am aware that many changes may be made and numerous details of construction may be varied through a wide range without departing from the principles of this 60 invention, and I, therefore, do not purpose

limiting the patent granted hereon otherwise than necessitated by the prior art.

I claim as my invention:

1. In a loose leaf binder, a pair of angular clamping members, a transversely extending ratchet bar upon one member, a longitudinally extending housing upon the other member, having slots through which said ratchet bar passes, a latch bar within said housing for engaging said ratchet bar and extending beyond one end of said binder, and yielding means acting upon said latch bar for maintaining the same in engagement with said ratchet bar. 70

2. In a loose leaf binder, a pair of clamping members, a transverse ratchet bar upon one member, a longitudinally extending housing upon the other member having a slot for receiving said ratchet bar and a latch bar slidably mounted in said housing 80 for engaging said ratchet bar, said latch bar extending through one end of said housing and having a finger piece thereon. 85

3. In a loose leaf binder having angular back members, said members each having a hinge portion at its outer edge, means for expansibly connecting said members, a post holding plate hinged to one member, posts upon said plate, and a post holding plate with posts thereon engageable with the hinge portion of the other member, said second plate being detachable to allow said first plate with sheets impaled thereon to swing to horizontal position with said second plate superposed upon said sheets. 90

4. In a loose leaf binder having expansible back members, a post holding plate hinged to one member, posts thereon adapted for retaining loose sheets, a second post holding plate, and cooperating means upon said second plate and the other back member for detachably engaging said second plate and other member, said second plate being detachable and swingable with said sheets to horizontal position in superposed relation 105 when said members are separated.

5. In a loose leaf binder, a pair of angular back members, means for adjusting the same toward and from each other, telescopic guide posts upon said members for guiding the same during their adjustable movements, a post plate hinged to one member, posts upon said plate adapted for retaining loose sheets, a second plate with posts thereon resting upon said guide posts and cooperating means upon said second plate and the other back member for detachably engaging said second plate with said other member whereby said second plate may be detached and swung upwardly with the loose sheets and in superposed relation therewith when said members are separated from each other. 115

6. In a loose leaf binder, a pair of angular back members having hinge portions at their outer edges, means for adjusting said mem- 130

bers toward and from each other, telescopic guide posts upon the ends of said members for guiding the same during their adjustments, a post plate hinged to one member, 5 posts thereon for receiving loose sheets, a plate with posts thereon resting upon said guide posts and having means detachably engaging the hinge portion of the other back member for the purpose set forth.

10 In testimony whereof I have hereunto subscribed my name at Philadelphia, Philadelphia county, Pennsylvania.

HUGH G. BUCHAN.
